Primary Examiner—Ian Simmons

[57] CLAIM

The ornamental design for a wound dressing, as shown and described.

DESCRIPTION

FIG. 1 is a front elevational view of the wound dressing of the present invention;

FIG. 2 is a back elevational view of the wound dressing of FIG. 1;

FIG. 3 is a left side elevational view of the wound dressing of FIG. 1;

FIG. 4 is a right side elevational view of the wound dressing of FIG. 1;

FIG. 5 is a top plan view of the wound dressing of FIG. 1; and,

FIG. 6 is a bottom plan view of the wound dressing of FIG. 1.

The broken lines on FIGS. 1 and 2 are indicative of backstitching.
